UNITED STATES PATENT OFFICE.

ALFRED L. SOHM, OF CHICAGO, ILLINOIS.

RADIATOR SIGNAL DEVICE.

Application filed January 24, 1925. Serial No. 4,589.

This invention relates to radiator signal devices and more particularly to a device adapted to be attached to the filling spout of an automobile radiator to indicate unusual thermal conditions existing therein.

An important object of the invention is to provide a pressure operated signal operable by an increase in pressure within the radiator due to the generation of steam therein and presenting a visible movable signal portion to permit the operator readily to determine the presence of abnormal conditions in the power plant of the vehicle.

A further object of the invention is to provide such a device which will be positive in action and wherein the visible signal is adapted to move to varying positions according to the pressure existing within the radiator without permitting the loss of steam from the radiator.

A still further object is to provide a device of the above mentioned character provided with a condensing chamber wherein water vapors or steam generated within the radiator will be condensed and returned to the radiator, thus minimizing the action of the visible signal when only a slightly abnormal condition exists within the radiator.

Other objects and advantages of the invention will become apparent during the course of the following description.

In the drawings, I have shown one embodiment of the invention. In this showing—

Figure 1 is a central vertical sectional view of the device applied to an automobile radiator, parts being shown in elevation,

Figure 2 is an enlarged central vertical sectional view of the device detached,

Figure 3 is a section taken on line 3—3 of Figure 2, and,

Figure 4 is a perspective view of the diaphragm.

Referring to the drawings, the numeral 10 designates an ordinary automobile radiator having the usual filling spout 11 and overflow pipe 12. The radiator is adapted to be connected at its upper end to the water jacket of the engine through the usual connection 13.

Referring to Figure 1, the numeral 14 designates a cross arm cap of the usual type threaded on the filling spout as shown. The cap is preferably hollow as shown and has a flat central upper portion 15 provided with

a central aperture for a purpose to be described.

The numeral 16 designates the signal device as a whole, comprising a preferably stamped circular base 17, the bottom of which is arranged against the flat top 15 of the cap. A depending tubular member 18 is secured to the base 17 and affords communication between the interior thereof and the interior of the radiator as will be obvious. The member 18 is preferably externally threaded as at 19 and a nut 20 is arranged thereon for securing the base and tubular member to the cap. A gasket 20 and spring washer 21 are preferably arranged between the nut 20 and the top of the cap 14 to maintain an air-tight joint. A nut 22 is arranged on the lower end of the tubular member and is provided with a screen 23 to prevent dirt and other foreign matter from passing from the radiator to the interior of the signal.

The signal further comprises a preferably vertically arranged circular chamber 24 secured to the base 17 by screws or the like 25. The chamber 24 is provided at its upper and lower ends with annular flanges 26 extending outwardly therefrom and a sleeve 27 surrounds the flanges 26 in contact therewith. The space between the flanges 26 and within the sleeve 27 provides a condensing chamber 28 which is adapted to communicate with the interior of the chamber 24 through openings 29.

The upper end of the chamber is closed as shown at 30 and the upper face of this closure member is preferably provided with concentric raised ridges 30 and 31 colored red to provide a visible signal to be described. The top portion 30 is provided with a depending cylinder 32 in which is mounted to reciprocate a plunger 33. A stem 34, preferably formed integral with the plunger 33, extends upwardly through an opening 35 in the top 30 as shown in Figure 1. A preferably stamped cap 36 is secured to the upper end of the stem 34 and extends downwardly to cover the colored portion 31 when the device is in normal position. A plate 37 may be connected between the stem 34 and the side walls of the cap 36 to more rigidly connect the latter to the stem.

The chamber 24 is provided with an interior annular flange 38 against which is

mounted a preferably rubber ring 39 to which is secured a diaphragm 40. I prefer to employ a diaphragm formed of gutta percha inasmuch as this material is adapted to resist the destructive action of the heat and steam from the radiator and to retain its elasticity through a long period of time. It will be obvious, however, that I may employ rubber or any other suitable elastic material in forming the diaphragm. A screen 41 is arranged against the lower face of the diaphragm and the chamber is provided with a second internal flange 42 against which the lower face of the screen 41 rests. It will be obvious that the flexibility of the ring 39, diaphragm 40 and screen 41 permits these members to be pressed in position within the groove formed between the flanges 38 and 42.

20 As shown in Figure 1, means is provided for preventing the escape of water vapors and steam from the overflow pipe. As shown a tubular member 43 is arranged in a rubber tube 44 clamped as at 45 to the lower end of the overflow pipe 12. The lower end of the rubber tube 44 is arranged within a second metallic tube 46 to the lower end of which is secured a whistle 47. A ball valve 48 is adapted to engage against 30 the other end of the tubular member 43 and is normally maintained in position by a coil spring 49. The lower end of the whistle may be provided with a drip opening 50 to permit the escape of any water which collects in the lower end of the whistle.

The operation of the device is as follows: With the valve 48 seated as shown in Figure 1, it will be obvious that no vapors can escape through the overflow pipe except when some considerable pressure is built up in the radiator. If some abnormal condition occurs within the engine to create a sufficient temperature within the radiator to boil the water therein the steam generated will pass upwardly through the tubular member 18 to the interior of the chamber 24 beneath the diaphragm 40. The pressure will stretch the diaphragm upwardly as shown in dotted lines in Figure 2 of the drawings and the diaphragm, contacting with the lower end of the plunger 33 will raise the latter upwardly, moving with it the cap 36 uncovering the colored upper face of the top 30, thus warning the operator of the existence of abnormal thermal conditions. It will be obvious that the operator need not depend upon the visibility of the colored signal face but may receive sufficient warning from the upward movement of the cap 36. The diaphragm 40 is preferably very thin and highly flexible so as to be sensitive to slight increases in pressure within the radiator. Under some conditions, however, abnormal conditions may exist in the engine due merely to unusual traveling con-

ditions such as ascending hills, traveling through sand, etc., and it is not desirable that the signal should operate under such conditions. As previously stated, vapors from the radiator are adapted to pass into the condensing chamber 28 wherein they are condensed and returned through the openings 29 to the radiator. When the temperature of the water rises to a point just above the boiling point, it has been found that the condensing action within the chamber 28 takes place with sufficient rapidity to greatly minimize, if not to wholly prevent the generation of pressure sufficient to raise the cap 36. Any additional pressures, however, are adapted to raise the signal cap 36 to give warning to the operator. It will be apparent that if the pressure generated within the radiator rises materially above the pressure necessary to fully raise the cap 36, the ball valve 48 will become unseated and permit the escape of the pressure fluid through the whistle 47, thus preventing damage to the radiator and affording an audible signal as a further warning to the operator. It will be apparent that the provision of the diaphragm and associated elements will prevent the leakage of steam through the upper end of the signal which has been found in practice to be very annoying when the pressure within the radiator reaches an extremely high point. The prevention of leakage and the condensation of the steam within the chamber 28 serves to retain the water within the radiator for a long interval of time.

It is to be understood that the form of my invention herewith shown and described is to be taken as a preferred example of the same, and that various changes in the shape, size and arrangement of parts may be resorted to without departing from the spirit of the invention or the scope of the subjoined claims.

I claim:

1. A device of the character described comprising a vertically arranged chamber adapted to communicate at its lower end with the interior of an automobile radiator, said chamber being provided intermediate its ends with a pair of spaced internal integral flanges, an elastic ring arranged between said flanges, an elastic diaphragm secured to said ring, said ring and said diaphragm being adapted to be frictionally held in position by said flanges, a cylindrical guide carried by said chamber above said diaphragm centrally thereof, a reciprocating plunger mounted in said guide and adapted to contact at its lower end with said diaphragm to be actuated thereby, said plunger extending upwardly beyond said chamber, and a cap carried by the upper end of said plunger and normally arranged adjacent the upper end of said chamber.

2. A device of the character described comprising a chamber provided intermediate its ends with an internal annular groove, the material forming said groove being integral with said chamber, one end of said chamber being adapted to communicate with the interior of an automobile radiator, an elastic diaphragm arranged in said chamber, an elastic ring secured against

one face of said diaphragm, the edges of said ring and said diaphragm being arranged in said groove and adapted to be frictionally retained therein by the walls thereof, and a signal adapted to be actuated by said diaphragm. 15

In testimony whereof I affix my signature.

ALFRED L. SOHM.
